UNITED STATES PATENT OFFICE

168,011

ROUNDABOUT

Floyd H. Wyman and Furman F. Taylor,
Westminster, S. C.

Application May 10, 1951, Serial No. 15,132

Term of patent 14 years

(Cl. D34—5)

To all whom it may concern:

Be it known that we, Floyd H. Wyman and Furman F. Taylor, citizens of the United States, residing at Westminster, in the county of Oconee, State of South Carolina, have invented a certain new, original, and ornamental Design for a Roundabout, of which the following is a specification, reference being had to the accompanying drawing, forming a part thereof.

In the drawing:

Fig. 1 is a top plan view of a roundabout showing our new design with two legs thereof partially omitted for convenience of illustration;

Fig. 2 is a side elevational view thereof;

Fig. 3 is an end elevational view; and

Fig. 4 is a perspective view.

This device presents substantially the same appearance on the opposite side as that shown in Fig. 2.

We claim:

The ornamental design for a roundabout, as shown and described.

FLOYD H. WYMAN.
FURMAN F. TAYLOR.
